A. J. SAGER

TIMER

Filed Nov. 3, 1923

UNITED STATES PATENT OFFICE.

ANDREW J. SAGER, OF WINCHESTER, VIRGINIA.

TIMER.

Application filed November 3, 1923. Serial No. 672,598.

To all whom it may concern:

Be it known that I, ANDREW J. SAGER, a citizen of the United States, and a resident of Winchester, in the county of Frederick and State of Virginia; have invented certain new and useful Improvements in Timers, of which the following is a specification.

The invention relates to timers of the commutator type for ignition systems of internal combustion engines in which a rotor or brush holder and its brush are revolved, at a predetermined speed ratio from the engine shaft, with relation to a stator, for causing successive makes and breaks in proper order 15 of the electrical circuits controlling the ignition devices.

The primary object of the invention is the provision of a compactly arranged device that is comparatively inexpensive in cost of 20 production, simple in construction and operation, and highly efficient in the performance of its functions of distributing the electrical currents as required. By the utilization of my invention a maximum friction 25 surface is provided between the moving and stationary contact members; uniformity in wear on the operating parts is insured; a reliable and close frictional contact is maintained, and compensation is made for wear 30 of parts, thus prolonging the durability of the timer. Means are provided for automatically cleaning the contacting members and preventing accumulation of gum in the path 35 of movement of the rotor, and other meritorious features are provided and advantages secured, as will be hereinafter set forth.

The invention consists in certain novel features of construction involving the rotor and stator, and combinations and arrangements 40 of elements embodied in these parts as will be specifically pointed out and claimed.

In the accompanying drawings I have illustrated one complete example of the physical embodiment of my invention where- 45 in the parts are combined and arranged according to the best mode I have thus far devised for the practical application of the principles of my invention. While I have shown the invention as adapted for use in 50 connection with a four cylinder engine it will be apparent that the timer may readily be converted for use in connection with other types of engines without departing from the spirit of my invention.

Figure 1 is a view in elevation at the inner face of the timer showing the timing shaft

in cross section, and indicating the wires for distributing the electrical current to each of four cylinders of an engine. The arm 6' of the head 11 is pivoted at 6" to the arm 6 of the holder. 60

Figure 2 is a sectional view through the timer showing the brush in contact with one of the contactors.

Figure 3 is a detail sectional view of the rotating brush and its holder. 65

Figure 4 is an inner face view of a portion of the housing cap.

Figure 5 is a detail sectional view at line 5—5 showing the manner of securing the housing ring, cap, and insulating block, as a 70 rigid structure.

For convenience of identifying and showing the relation of parts I have designated 1, 2, 3, and 4; the wires leading from the timer to the corresponding cylinders of the 75 engine for distributing the electrical currents to the spark plugs.

The driving shaft 5 for the timer is driven in suitable manner at a predetermined speed ratio from the crank shaft of the engine, 80 and the rotor or brush-holder 6 is provided with a hub 7 which is fixed to revolve with the shaft by means of a slot or notch 8 fitting around a retaining pin 9 which is carried by the shaft. A cup washer 10 encircles the shaft at the side of the hub and holds the pin against displacement. 85

At its outer end the holder or arm 6 is fashioned with a hollow head 11 in which is carried the brush 12, preferably made of 90 copper and fashioned with a conical contact point 13. The brush as seen in Figure 3 is hollow and of a size to fit snugly within the hollow head 11 and permit rotary movement of the brush with relation to its holder. 95

The stator housing includes a metal ring 15, a fiber insulating block 16, and the housing cap 17, which may be fashioned with a grooved edge 18 to fit against the circular edge of the metallic ring, and these three elements are secured together to form a rigid structure which is supported in usual manner. Fastening screws 19 are shown passing through the wall of the cylindrical metal housing portion 15 and also through perforated lugs 20 of the housing cap, which lugs are fitted into complementary sockets 21 in the insulating block 16, and the screws penetrate the insulating block also to rigidly secure these members together. By this construction of parts they may readily be as- 100 105 110

sembled and fastened together, and when required the housing may be dismantled by first removing the screws to permit separation of the parts.

5 The insulating block is provided with an open center 22 to accommodate the shaft 5, and the retaining nut 23 on the end of the shaft is accommodated in the recess 24 in the inner face of the housing cap 17, the cap 10 forming a closure and backing for the insulating block as indicated.

In the face of the insulating block is formed an annular groove 25, V-shaped in cross section and complementary to the 15 conical brush point 13 which is adapted to travel therein. At regular spaced intervals in the insulating block are provided four sockets 16' which intersect the annular groove and receive and retain the respective 20 contactors 1^a, 2^a, 3^a, and 4^a, which are of suitable metal and arcuate in shape. The faces of the several contactors are flush with the face of the insulating block, and across 25 the face of each contactor is disposed a V-shaped groove 26 alined with and forming a continuation of the groove 25 in the insulating block. In this manner a continuous annular path is provided for the rotating conical brush which travels through the continuous groove in close frictional contact 30 with the opposed faces of the groove and passes successively through the several contactors. By means of the expansion spring 14 of the brush the latter is held in positive 35 contact with the walls or faces of the groove, and as the brush holder rotates, the brush itself also revolves with relation to the holder, and rolls through the groove in contact with its opposite walls. In this 40 manner a maximum area of contact is secured between the rolling brush and the grooved contactors, the spring holds the brush to the contactors and adjusts their relation to compensate for wear, the brush cleans and 45 maintains the walls of the groove in a cleansed condition free from accumulation of gum that would otherwise develop from the presence of oil as a lubricant, and the closing and opening movements of contact 50 of the brush with the successive contactors is made with an absence of a distinct burning or flash of electricity that is present in many devices of this character.

The metallic contactors are of the approximate width or thickness of the insulating block, and the rear faces of the contactors are backed against the inner face of the cap 17. Each contactor is fashioned with a binding post or terminal 27 and 55 clamp nuts 28 and 29 for attachment of the respective lead wires 1, 2, 3, and 4, and the inner face of the cap is fashioned with recesses 30 for the accommodation of these

65 terminals. The lead wires preferably are brought out through the housing at one side thereof, and for this purpose each recess 30 has connected therewith a groove 31 in the inner face of the cap 17 for the accommodation 70 of the respective wires. The wires leading to the respective cylinders may be identified by numbers corresponding to the cylinders, and these identification marks may be placed on the housing cap adjacent to the respective grooves or channel outlets 75 at the side of the cap.

From the above description taken in connection with my drawing the construction and operation of the timer will be evident. It will be understood that I do not confine myself to the specific shapes and sizes of 80 the elements, nor to materials used, nor the number of parts shown for making and breaking the ignition circuits, and I contemplate making changes in the illustrated structure within the scope of my claims 85 without departure from my invention.

Having thus fully described my invention, what I claim as new and desire to secure by Letters Patent is—

1. In a timer the combination with an insulating block having an annular groove and a series of spaced contactors intercepting said groove and fashioned with complementary groove portions, of a hollow rotatable brush holder and a relatively rotatable brush carried thereby perpendicular to the face of the insulating block and conforming to the shape of the groove, and a spring within the hollow holder for maintaining contact of the brush with said contactors. 90

2. In a timer the combination with an insulating block having an approximately V-shaped annular groove in its face and a series of spaced similarly grooved contactors forming a continuous groove, of a rotatable brush holder, a relatively rotatable brush carried by said holder and fashioned with a conical contact member disposed perpendicular to the face of the block for co-action with said contactors, and a spring within the holder and engaging the brush for maintaining the brush in position. 95

3. In a timer the combination with a housing ring, a grooved insulating block within the ring and a housing cap, means for fastening these members as a rigid structure, a series of spaced grooved contactors fixed in the block and forming a continuous annular groove in the face of the block, a rotatable brush holder, and a relatively rotatable conical brush disposed perpendicular to the face of the block and carried by said holder for co-action with the grooved contactors. 100

ANDREW J. SAGER.
